UNITED STATES PATENT OFFICE.

IRVING J. McCULLOUGH, OF WALNUT PARK, CALIFORNIA.

OUTSIDE PIPE CUTTER.

Application filed July 7, 1927. Serial No. 203,892.

This invention relates to a tool adapted to be passed over tubular members such as pipes, casings and the like, and then to be manipulated so as to sever the same. More particularly, the present invention may be embodied in a tool for cutting drill pipe in wells. In many instances, drill pipes become stuck in the well hole and it is necessary or advisable to part the string of pipe at a point below the surface. The present invention is adapted for such use, it being placed over a pipe and lowered in the hole to the place the cut is to be made, then manipulated to make the cut and withdrawn. It is a primary object of this invention to provide a cutter of the character described which may be lowered over a pipe to be cut by means of the usual wash string and the cutters projected by rotation of the tool in one direction and retracted by rotation in the other direction. A more specific object of this invention is the provision of a tool of the character described which has a cutter carrier adapted to embrace the pipe, cutters mounted thereon projectable inwardly from said carrier, and an actuator for projecting said cutter operable by rotation of the tool body which may be effected by means of the usual wash string by which the tool is raised and lowered in the hole.

With the foregoing objects and other objects and corresponding accomplishments in view, the present invention consists in the features of construction, combination and arrangement of parts hereinafter more fully described, reference being had to the accompanying drawings, in which:

Fig. 1 is an elevation partly in section through a complete tool showing it in position over a drill pipe and ready for performing the cutting operation, the section through the shell of the tool being on the line 1-1 of Fig. 2; Figs. 2, 3, and 4 are sections as seen upon the lines correspondingly numbered in Fig. 1 the blades being shown in cutting position, and Fig. 2 on an enlarged scale; Fig. 5 is a section corresponding to Fig. 3 showing the blades retracted; Fig. 6 is a modified form of the tool in elevation; and Fig. 7 is an axial section as seen on the line 7-7 of Fig. 6.

Referring with more particularity to the drawing and especially Fig. 1, a drill pipe string which is to be severed is indicated generally by 10. It is formed of joints of

pipe connected by collars, one of which is indicated by 11. Disposed over the drill pipe is the cutter.

A tubular collar 12 is counterbored and internally threaded to receive the pipe 13 of the wash string or pipe by which the cutter is manipulated. Collar 12 is externally threaded and attached thereto is a shell 14, carrying at the bottom a shoe 15. Secured to the shell and resting upon the shoe is a blade carrier 16 of ring form. The ring is cut away at its upper portion to form spaces 17 for knife cutters. Mounted upon longitudinally extended pivot pins 18 are cutter units comprising bodies 19 to which are secured blades 20. The blades are detachably mounted upon the bodies 19 by means of pins, one of which indicated by 21, extends upwardly and is engaged by a leaf spring 22. The other end of the leaf spring is mounted in fixed position upon the carrier ring 16 and tends to swing the blade outwardly. The noses of the blade units are inclined as best indicated by 23 in Fig. 2. The structure just described comprises a cage having the cutter units pivotally mounted thereon so that they may be swung to and from the work to be severed, namely, the pipe 10.

For the purpose of projecting the knives inwardly into cutting position, an actuator is provided. The actuator comprises a ring 24 having depending from its lower side wedges 25. These wedges have inclined faces 26 for confronting the corresponding inclined faces 23 of the cutter unit. Extending upwardly from the ring are spring fingers 27 having teeth at their upper ends extending lengthwise. The ends of the fingers are arranged to engage the work so as to frictionally and yieldably grasp the same and resist turning.

Suppose a drill pipe string 10 is to be cut, the tool is lowered over the drill pipe string by means of the wash string 13. It is moved to the position at which the cut is to be made. Obviously, the tool would slip over the drill string, the fingers 27 sliding over the joint and coupling. When the tool is in position, it is manipulated to perform the cut, by turning in a right hand direction. This causes the cage with its cutter to be moved tending to drag along the actuator. Movement of the actuator is resisted by contact of the fingers 27 with the spring. The wedges 25 are forced against the noses of the cutter unit, and move the latter inwardly

against the drill string so that the knives are in position to cut by continued rotation of the tool. The drill pipe having been cut, the tool is backed up so that the wedges are 5 retracted and the springs 22 move the blade outwardly to their non-working position. The severed pipe and tool may then be elevated, or in some instances, the tool may be elevated by forcing it upwardly, the spring 10 fingers 27 either breaking or moving over the coupling.

In Figs. 6 and 7, a modification of the tool is shown, the only difference residing in the spring fingers attached to the actuating ring. In order to shorten the description, parts in Figs. 6 and 7 corresponding to those shown in Figs. 1 to 5 are marked with corresponding reference numbers having the letter "a" added. However, the spring 20 fingers 27^a are bent upwardly at the ends as indicated by 28 so as to clear the collars 11^a and ride over them, if it is desired to move the cutter upwardly. With structure shown in Figs. 6 and 7, the severed upper 25 portion of the string of pipe must be raised by separate means.

It will be noted that the device is operable at any place in the string. Cutters have heretofore been made which depend 30 upon spring fingers or arms or equivalent devices abutting the under shoulder of a collar and being moved longitudinally to project the cutters. The present structure is only dependent upon the drag in a rotary 35 direction, and is not dependent upon any protuberance upon the string of pipes to be cut for its operation.

What I claim is:

1. In a device of the class described, a cage 40 adapted to be rotated, cutter units mounted thereon so as to be projectable from retracted position toward the work into cutting position, an actuator mounted on said cage for turning movement thereon and for rotation therewith and including means to project said cutter units upon relative rotation of said cage and actuator in one direction, and means to yieldably resist turning of said actuator upon rotation of said cage.

2. In a device of the class described, a cage 50 adapted to be rotated, cutter units mounted thereon to be projectable from retracted position toward the work into cutting position, an actuator mounted on said cage for turning movement thereon and for rotation therewith and including means to project said cutter units upon relative rotation of said cage and actuator in one direction, and members on said actuator engageable with said work to yieldably resist turning of said actuator upon rotation of said cage.

3. In a device of the class described, a cage 60 adapted to be rotated, cutter units pivotally secured to said cage so as to be pro-

jectable from retracted position toward the work into cutting position, an actuator mounted on said cage for turning movement thereon and for rotation therewith and including peripherally inclined wedges 70 engageable with said units so that upon relative rotation of said cage and actuator in one direction said units will be projected, and means to yieldably resist turning of said actuator upon rotation of said cage. 75

4. In a device of the class described, a cage adapted to be rotated, cutter units pivotally secured to said cage so as to be projectable from retracted position toward the work into cutting position, an actuator mounted on said cage for turning movement thereon and for rotation therewith and including peripherally inclined wedge means 80 engaged with said units so that upon relative rotation of said cage and actuator in one direction said units will be projected, and members on said actuator engageable with said work to yieldably resist turning of said actuator upon rotation of said cage. 85

5. In a device of the class described, a cage 90 adapted to be rotated, cutter units mounted thereon to be projectable from retracted position toward the work into cutting position, an actuator mounted on said cage for turning movement thereon and for rotation therewith and including means to project said cutter units upon relative rotation of said cage and actuator in one direction, and spring fingers secured at one of their ends to 95 said actuator and free at the other for grasping said work to yieldably resist turning of said actuator thereon. 100

6. In a device of the class described, a cage 105 adapted to be rotated, cutter units mounted thereon to be projectable from retracted position toward the work into cutting position, an actuator mounted on said cage for turning movement thereon and for rotation therewith and including means to project said cutter units upon relative rotation of said cage and actuator in one direction, and spring fingers secured at one of their ends to said actuator and free at the 110 other ends for grasping the work to yieldably resist turning of said actuator thereon, the ends of said fingers being inclined to ride upwardly over the projections on said work. 115

7. In a device of the class described, a 120 cage, a cutter unit mounted thereon to be moved laterally so as to be moved against or away from the work, an actuator mounted on said cage for rotatable movement, there being wedge means on said actuator having a laterally extending inclined surface 125 engageable with said unit whereby to move said unit laterally upon relative rotation of said cage and actuator, and means on said actuator for grasping said work to resist turning of said actuator thereon. 130

8. In a device of the character described, a cage, a cutter unit mounted thereon to be moved laterally so as to be moved against or away from the work, an actuator mounted on said cage for rotatable movement, there being wedge means having a laterally extending inclined surface on said actuator engageable with said unit whereby to move said unit laterally upon relative rotation of said cage and actuator, and spring fingers on said actuator for frictionally contacting the work so as to yieldably resist turning of said actuator.

9. In a device of the character described, a cage adapted to be rotated, cutter units pivotally secured to said cage and mounted on axes extending longitudinally thereof, whereby to be swung to and from the work, an actuator mounted on said cage for rotatable movement thereon and rotation therewith, there being a peripherally inclined surface on said actuator for each unit disposed to engage the latter whereby to move said units laterally upon relative rotation of said cage and actuator, and spring fingers on said actuator for frictionally contacting the work so as to yieldably resist turning of said actuator, the ends of said fingers being inclined to ride upwardly over the projections on said work.

10. In a device of the class described, a body of shell form for embracing the work to be severed, cutter units pivotally secured to the wall of said body on axes extending longitudinally of the body whereby to be swung to and from the work, an actuator mounted in said body for rotatable movement thereon, there being inclined surfaces on said actuator for each unit disposed to engage the latter whereby to swing said unit inwardly upon relative rotation of said shell and actuator, and means on said actuator for grasping said work to resist turning of said actuator thereon.

11. In a device of the class described, a

body of shell form for embracing the work to be severed, cutter blades pivotally secured to said body on longitudinally extending axes whereby to be swung inwardly and outwardly from the work, an actuator mounted in said body for rotatable movement, there being inclined surfaces on said actuator for said blades disposed to engage the latter whereby to swing said blades inwardly upon relative rotation of said body and actuator, and means on said actuator for grasping said work to resist turning of said actuator thereon.

12. In a device of the class described, a body of shell form for embracing the work to be severed, peripherally spaced cutters pivotally secured to said body on longitudinally extending axes whereby to be swung inwardly and outwardly from the work, an actuator ring mounted within said body for rotatable movement thereon, there being an inclined surface on said ring for each cutter disposed to engage the latter whereby to swing said cutter inwardly upon relative rotation of said body and actuator in one direction, and means on said actuator for grasping said work to resist turning of said actuator thereon.

13. In a device of the class described, a body of shell form, cutter blades peripherally spaced on said body and mounted on longitudinally extending axes whereby to be swung inwardly and outwardly from the work to be severed, an actuator ring mounted within said body for rotatable movement thereon, said ring having a wedge for each blade disposed to engage the latter whereby to swing said blade inwardly upon relative rotation of said body and actuator, means on said actuator for grasping the work to resist turning of said actuator thereon.

In witness that I claim the foregoing I have hereunto subscribed my name this 23rd day of June, 1927.

IRA J. McCULLOUGH.
